UNITED STATES PATENT OFFICE.

EDWARD M. BENTLEY, OF BOSTON, MASSACHUSETTS.

ELECTRIC-LINE SWITCH.

SPECIFICATION forming part of Letters Patent No. 446,418, dated February 17, 1891.

Application filed February 15, 1890. Serial No. 340,510. (No model.)

To all whom it may concern:

Be it known that I, EDWARD M. BENTLEY, a citizen of the United States, residing at Boston, Massachusetts, have invented certain new 5 and useful Improvements in Electric-Line Switches for a Suspended Line-Conductor of an Electric Railway, of which the following is a specification.

My invention is illustrated in the accompanying drawings, in which—

Figure 1 is a perspective view of my switch in position. Fig. 2 is a side elevation thereof. Fig. 3 is a plan thereof, and Fig. 4 is an end elevation with the line-conductor in section.

15 My invention relates to an overhead line-conductor for an electric railway, which is divided into sections; and it consists in a switch for connecting the sections, attached directly to the line-conductor, and of such a form as 20 not to interfere with the passage of the trolley or contact device along the line.

This switch is operated by means of an insulated wire or cord, which extends to posts upon opposite sides of the street, and thence 25 passing through a pulley terminates in a box on the post. In this way means are provided for readily cutting out of circuit temporarily any one or more of the sections of the line-conductor, as it is often desirable to do when 30 a fault or ground occurs, or when other exigencies of service require.

Referring to the drawings, A and B are two adjoining sections of a suspended conductor. The adjoining ends of the two sections are 35 each provided with an offset C, firmly brazed to its upper surface, and so shaped as to permit the passage of the trolley-wheel below the wire. The two offsets C are placed end to end with an intermediate piece of insulating material D, and an insulating-bolt P is then passed through, and the two ends of the wire are thus firmly connected. Above the two offsets C and electrically connecting them I provide the pivoted switch-plate E, which 40 at one end is pivoted to one offset C and at the other end engages with the contact-spring K upon the other offset.

The switch is normally in a position to bridge the insulation and close the line-circuit; but it may be opened or closed at will 45 by means of insulated wires L and R, which

extend from it to poles upon opposite sides of the street, and thence passing through pulleys each terminates in a box attached to the post.

55

In the example shown L and R are wires provided with an insulating-link S; but it is obvious that a cord may be employed instead, and it is also obvious that the cords may come to the same post, one of them being attached 60 to the switch at a point upon the opposite side of its pivoting-point.

It is furthermore obvious that the switch may be operated in one direction by a spring and in the other direction by a cord; but I 65 prefer to operate it positively in both directions.

What I claim as new, and desire to secure by Letters Patent, is—

1. The combination, in an electric railway, 70 of adjacent sections of a line-conductor suspended above the street, normally connected together electrically to form one of the branches of a two-wire circuit between which the motors are in multiple arc, and a switch 75 pivoted upon the upper side of one section, out of the path of travel of the contact device and permanently in circuit therewith, and adapted to make and break contact with the other section, as described.

80

2. The combination, with a sectional suspended line-conductor for an electric railway, having enlarged conducting-offsets upon the ends of adjacent sections thereof, of a switch pivoted upon one of said offsets and adapted 85 to swing into and out of engagement with the other offset, for the purpose described.

3. The combination, with a suspended line-conductor for an electric railway, divided into insulated sections, of a manually-operated 90 switch normally connecting two sections of the conductor, and an operating cord or wire connected thereto and extending to the side of the street to a convenient operating point.

4. The combination, with adjacent sections 95 of line-conductor, of an offset on the end of each conductor, intervening insulating material between the two offsets, an insulating-bolt, and a switch bridging the insulating material and connecting the two offsets.

100

5. The combination, with a suspended line-conductor divided into sections, of an offset

on the end of each section, insulating material between the two offsets, a switch pivoted to one offset and adapted to connect with the other, and an operating device for the switch 5 extending to the side of the street.

6. The combination, with a suspended line-conductor forming a substantially continuous bearing-surface for a traveling contact device, of a switch out of the path of travel 10 of the contact device, joining two adjacent

sections thereof electrically, and an operating cord or wire extending from said switch to a side post and there provided with an operating-extension reaching down along the post to a convenient position.

EDWARD M. BENTLEY.
